UNITED STATES PATENT OFFICE.

CARBON P. DUBBS, OF WILMETTE, ILLINOIS, ASSIGNOR TO UNIVERSAL OIL PRODUCTS COMPANY, OF CHICAGO, ILLINOIS, A CORPORATION OF SOUTH DAKOTA.

PROCESS FOR TREATING HYDROCARBON OILS.

Application filed December 17, 1921. Serial No. 523,113.

This invention relates to a method for treating hydrocarbon oils to produce therefrom products of lower boiling points.

This application is a continuation in part 5 of my co-pending application Serial No. 204,527, filed Nov. 30, 1917.

Among the salient objects of the invention are to provide an improved process in which the heated hydrocarbons are circulated 10 through a coil still and then passed to a condenser, and during such treatment subjected to the pressure of the generated vapors; to provide a process in which the temperature and pressure are readily and accurately controlled; to provide a process 15 wherein the circulation of the hydrocarbons being treated is readily and accurately controlled; to provide a process which can be operated continuously; to provide a process 20 which avoids the danger of the tubes in which the hydrocarbon is heating from being burned out by preventing the precipitation of carbon on said tubes, this being accomplished by means of the rapid circulation of 25 the oil through said tubes; to provide a process in which such products that are only partly converted to the desired low boiling point are returned and further treated in the distilling tubes; to provide a process 30 where, by means of air-cooled condenser, the grade of distillate allowed to pass from the system is controlled, and such distillate not up to a desired grade is condensed and automatically returned to distilling coils and 35 redistilled; to provide a process in which the heating tubes and the distilling tubes are maintained in a furnace held within well defined temperature ranges, and the oil caused to circulate through said heating 40 tubes at such velocity as to prevent any great amount of carbon depositing on said tubes; and, in general, to provide an improved process of the character referred to.

In the drawings:

45 Fig. 1 and Fig. 1^a together show a side elevation partly in section and with other parts broken away.

Fig. 1^b is a side view of the liquid level regulator and diaphragm valve, shown in fragmentary section.

50 Fig. 2 and Fig. 2^a are a plan view of the construction shown in Figs. 1 and 1^a.

Fig. 3 is an end elevation of the condensing members.

Fig. 4 is a view, partly in elevation and 55 partly in section, of the heating coils.

Referring to the drawings, A¹ are the furnaces in which the heating tubes and distilling tubes are positioned. A² are the tunnels through which the fire for heating 60 the furnaces passes. A³ are the furnace flues. A⁴ is the flue stack.

B¹ constitute parallel substantially level heating tubes, and B² constitute substantially level distilling tubes. B³, B⁴, B⁵ and 65 B⁶ are return T's on the heating tubes. B⁷, B⁸ and B⁹ are return T's on the distilling tubes. B¹⁴ and B¹⁵ are fittings around the tubes for anchoring the particular tubes shown. All the tubes extend through the 70 furnace walls and are free to expand independently thereof, with the exception of where the two tubes are anchored. B¹⁶ and B¹⁷ are braces for supporting the tubes B¹ and B². 75

C¹ is a feed line from any source of supply to pump C², and in this line is throttle valve C³. C⁴ is the charging line from the pump to the heating tubes B¹, and in this line is the throttle valve C⁵. C⁶ and C⁷ are 80 motors for operating the pumps C² and C⁸. C⁸ is a pump which is supplied through line C⁹ branching from the suction line C¹. C¹⁰ is the discharge line connecting this pump with charging line C⁴, and branching off 85 of discharge line C¹⁰ is a branch line C¹¹ which connects with suction line C⁹ and having positioned on it a pressure relief valve or by-pass valve C¹². C¹³ is a meter of any standard make suitable for the work in hand. 90 C¹⁴ is a standard make check-valve. C¹⁵ is an automatic liquid level regulating gauge, and the one shown here is that which is furnished by the "S-c" Regulator Company of Fostoria, Ohio, and C¹⁶ shown attached to 95 the end of the distilling tubes B² operates to open and close the valve C¹⁶, which valve is connected with C¹⁵ by a diaphragm C¹⁷, valve C¹⁶ being positioned in the supply line C⁴. It will be understood that any suitable method may be employed for regulating the level of the liquid in the distilling tubes 100 B². As this regulator is of standard equipment and operates on well-known principles,

and the valve operated by a diaphragm is of standard make and well understood. I do not go into the description of same here, nor do I claim any part of the regulator itself as new.

10 B^{10} is a fitting connecting adjacent heating tube B^1 to the supply line C^4 . B^{11} is the fitting on the end of heating tubes B^1 through which the oil in same is discharged into line D^1 . The line D^1 is connected to the bottom of the fitting B^{12} , which is secured to the distilling tubes B^2 . The oil is discharged out through the bottom of the fitting B^{13} by means of the line E^1 and through 15 cooling tank E^2 , and then to any suitable storage, not shown, and between said storage and cooling tank E^2 is positioned, in line E^1 , a throttle valve E^3 to control the rate of flow of the residuum through the line E^1 ; 20 and a similar valve, marked E^4 , is positioned in the line E^1 for obtaining samples of the residuum flowing through the line E^1 .

F^1 is a centrifugal pump. F^2 is a motor for operating same. F^3 is the suction line to 25 the pump from the heating tubes B^1 which comes out of the bottom of the fitting marked B^6 . F^4 is the discharge line which enters the side of the fitting marked B^{10} on the end of the heating tubes marked B^1 . F^5 is a carbon 30 trap on the end of the distilling coils attached to the bottom of the fitting marked B^{12} .

G^1 , G^2 , G^3 and G^4 are upwardly inclined vapor lines leading off of the distilling tubes 35 B^2 . Lines G^1 and G^4 connect with a manifold G^5 , which manifold connects by pipe G^6 to fitting B^8 attached to the distilling tubes B^2 . Lines G^2 and G^3 connect to a manifold G^7 , which manifold connects, by means of 40 pipe G^8 , to the top of fitting B^{13} on the end of the distilling tubes B^2 . These vapor lines G^1 , G^2 , G^3 and G^4 are connected at their upper ends to a common header G^9 , and have positioned on them throttle valves G^{10} , G^{11} , 45 G^{12} and G^{13} . Said manifold G^9 is connected to a top manifold G^{14} by means of bent pipes G^{15} to G^{26} , and to the center of the top manifold G^{14} is connected pipe G^{27} which connects, in turn, to the coil G^{28} contained in the 50 water tank G^{29} . From the coils G^{28} the condenser extends through pipe G^{30} into the receiving tank H . From the pipe G^{30} is a branch pipe G^{31} having a pressure indicating gauge G^{32} , and out of the pipe G^{31} extends pipe G^{33} on the end of which is a valve G^{34} . This valve and gauge may be situated 55 in the tail house and afford means for there regulating the pressure.

On the tank H are glass liquid gauges H^1 60 and H^2 , pressure relief valve H^3 , draw valves H^4 , H^5 and H^6 , and pressure gauge H^7 . H^6 is for use in case water is to be drawn off before draining the distillate out through the valve H^5 . H^4 is a valve for use in an 65 emergency, for example: when one of the

other valves is removed for repair or renewal, and which valve is superficial for showing the workings of the apparatus.

J^1 , J^2 and J^3 are supports for the receiving tank H . K is a support for the pipes shown. 70

L^1 is a standard indicating pyrometer and is connected with different thermosticks, which thermosticks are positioned in the furnace in which the tubes B^1 and B^2 are positioned. L^2 is a standard temperature recording instrument and is connected to a thermostick by a cable, and which thermostick is positioned inside the manifold G^{14} . L^3 is a standard temperature recording instrument connected, by means of a cable, to 75 thermosticks, which latter are positioned, one in the heating coils, to give the temperature of the oil contained therein, and one positioned in the large distilling coils, to give the temperature of the oil contained 80 therein. L^4 is a standard indicating liquid gauge which is connected by tubing to the receiving tank H and shows the depth of the liquid contained in the receiving tank H .

L^5 is an electric switchboard of standard 85 make, which board contains the standard knife switch for breaking or completing the circuit in operating the charging pump C^2 ; also a knife switch for breaking or completing the electric circuit for controlling the motor C^6 which operates the circulating pump C^8 ; also a knife switch for breaking 90

or completing the electric circuit for controlling the electric circulating pump F^1 , also a knife switch of standard make for 95 breaking or completing the electric current for supplying the electric lights in the plant, all of which are enclosed in the house built beneath the water cooling tank C^{29} .

M^1 is the gas main for supplying the furnace in which the tubes B^1 and B^2 are contained, and on this line is positioned throttle 100 valve M^2 .

N^1 , N^2 , N^3 and N^4 are supports for the extensions O^4 and O^2 , which extensions are 105 simply housing over the ends of the heating tubes B^1 and the distilling tubes B^2 , which housing is to prevent more or less cooling effect that would be caused by leaving them open to the atmosphere, and also to prevent subjecting the ends to varying temperatures.

Describing now the operation of the process, the material to be treated is drawn from any suitable source of supply through the line C^1 , by and through centrifugal pump C^2 , through line C^4 into the heating tubes B^1 , then through line D^1 to distilling tubes B^2 , and when these latter heating tubes have 110

been filled to desired level, pump C^2 is shut down and valve C^3 on line C^1 and valve C^5 on line C^4 are closed, and normally remain closed on the rest of the run. Heat is applied to the furnace A^1 , and as soon as a 115

desired vapor pressure has been created on the apparatus then supply pump C^8 is 120 shut down and valve C^6 on line C^8 is closed, and valve C^7 on line C^9 is opened, and the apparatus is 125

130

started in operation and obtains its supply of raw material through line C⁹ and discharges through line C¹⁰ into line C⁴, valve C¹⁸ being opened; and should the level of the liquid in the distilling tubes B² be of the proper height, then the liquid level regulator C¹⁵ will, by means of diaphragm C¹⁷, close the valve C¹⁶ on the supply line C⁴, and the back pressure thus created on the line C⁴ will force open the pressure relief valve C¹² and by-pass the oil from the discharge side of the pump C⁸ back into the suction line C⁹, and this operation will continue until the level in the distilling tubes B² drops to a sufficient point to permit the valve C¹⁶ to be automatically opened, thus admitting more raw material into the heating tubes B¹ and B².

The pump F¹ is put and maintained in operation, and the oil in the heating tubes B¹ made to circulate by drawing the oil through suction F³ and discharge back into the tubes through discharge F⁴.

The residuum formed in the distilling tubes B² can be drawn off either intermittently or continuously through line E¹ through cooling coil contained in tank E² and from there to any suitable storage. The quantity that is drawn off is regulated by means of valve E³ positioned in line E¹, and samples of said residuum may be obtained at any time through valve E⁴ in line E¹.

The vapors generated pass up through lines G¹, G², G³ and G⁴ and into manifold G⁵, and from there out through pipes G¹⁵ to G²⁶ and into manifold G¹⁴. All the vapors that are condensed up to this point are drained back into the distilling tubes B², while the remaining vapors pass through line G²⁷, through cooling coils G²⁸ immersed in water in tank G²⁹, and from there pass through line G³⁰ into receiving tank H, from which they may be drawn off intermittently or continuously through valves H⁵ and H⁶.

It will be seen that this method provides a process for automatically and continuously treating petroleum for the production of lower boiling point products, and by means of the circulation of the liquid into heating tubes B¹ permits of the furnace in which the tubes are positioned being maintained at a considerably higher heat without injurious effect to the oil, and prevents any substantial deposit of carbon on the tubes.

The method while disclosed as being operated with a liquid level regulator, may be as easily operated and in some cases preferably,

by disconnecting the liquid level regulator and introducing fresh oil from time to time as the operator desires. In certain cases where a certain liquid level is maintained in the vaporizing chamber, the conditions of cracking cannot be maintained properly and it is necessary at times to either raise the liquid level or allow it to lower to a point where more desirable and advantageous conditions of cracking are obtained. Also, the local circulation which is maintained in the heating zone through the pump F¹ during the operation of the process, may be functioned during the initial stages to raise the oil to a cracking temperature before passing it to the distilling zone, that is, by circulating the oil only through the heating zone during the initial heating, it is possible to raise the oil quicker to the desired temperature than where a greater quantity of oil is to be heated and the same must pass continuously through the entire system.

The entire system is preferably subjected to a vapor pressure of from 50 to 500 lbs., although the pressure will vary with the conditions. The temperature of the oil will preferably vary from 500° to 1000° Fahr., although I do not limit myself to these figures. The pump is preferably operated so as to cause a relatively rapid circulation of the oil in the heating tubes.

I claim as my invention:

1. A process for cracking hydrocarbon oil, which consists in supplying oil under pressure to a heating zone, in passing heated oil from the heating zone to a distilling zone, in taking off vapors from the distilling zone, in controlling the quantity of oil supplied to the heating zone by the liquid level of the oil maintained in the distilling zone and in continuously maintaining a local cyclic circulation of the oil undergoing treatment in the heating zone.

2. A continuous process for cracking oil consisting in pumping a stream of oil to a heating coil, where it is locally circulated and raised to a cracking temperature, in delivering the highly heated oil to a distilling zone, in automatically maintaining a uniform quantity of oil in the distilling zone by returning a portion of the oil being pumped to the heating zone to the inlet of the pump employed in the process and in maintaining a super-atmospheric vapor pressure on the oil undergoing conversion.

CARBOÑ P. DUBBS.
